US0D1066903S

(12) **United States Design Patent** (10) **Patent No.:** **US D1,066,903 S**
(45) **Date of Patent:** **** Mar. 18, 2025**

(54) **BABY CARRIER**

(71) Applicant: **Haixia Wei**, Fujian (CN)

(72) Inventor: **Haixia Wei**, Fujian (CN)

(*) Notice: Patent file contains an affidavit/declaration under 37 CFR 1.130(b).

(**) Term: **15 Years**

(21) Appl. No.: **29/959,586**

(22) Filed: **Aug. 26, 2024**

(51) LOC (15) Cl. **03-01**

(52) U.S. Cl.

USPC **D3/214**

(58) **Field of Classification Search**

USPC D3/213, 214, 215

CPC A47D 13/02; A47D 13/025

See application file for complete search history.

Michael Bartholomew

(57) **CLAIM**

The ornamental design for a baby carrier as shown and described.

DESCRIPTION

FIG. 1 is a front, left, and top perspective view of a baby carrier, showing my new design;

FIG. 2 is a rear, right, and bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

The broken lines in the drawings depict portions of the baby carrier that form no part of the claimed design.

1 Claim, 8 Drawing Sheets
